UNITED STATES PATENT OFFICE.

CHARLES E. HOBSON, OF FREMONT, IOWA.

WINDOW-SHADE.

1,281,006.

Specification of Letters Patent.

Patented Oct. 8, 1918.

Application filed October 11, 1917. Serial No. 195,981.

To all whom it may concern:

Be it known that I, CHARLES E. HOBSON, a citizen of the United States, residing at Fremont, in the county of Mahaska and 5 State of Iowa, have invented certain new and useful Improvements in Window-Shades, of which the following is a specification.

This invention relates to window shades 10 and more particularly to a series of coöperating shade sections adjustably mounted in a manner that will permit the shade to be raised from the bottom, lowered from the top, or opened intermediate its ends.

One of the particular objects of the invention is to provide an adjustable shade of this character that will avoid the necessity of the usual shade roller now generally employed on window shades.

A further object of the invention is to provide a series of vertically adjustable shade sections, so arranged with respect to each other that they may be raised or lowered collectively or individually, whereby any portion 25 of the window may be exposed to permit the light to pass through.

A further object of the invention is the provision of a window shade which consists of comparatively few parts and is simple in 30 construction, but durable and well adapted to withstand the rough usage to which devices of this character are ordinarily subjected.

For a full description of the invention 35 and the advantages and merits thereof, reference is to be had to the following description and the accompanying drawings, wherein is illustrated the preferred form of my invention, in which:

Figure 1 is a fragmentary vertical section of a window frame showing my invention applied thereto.

Fig. 2 is a fragmentary front elevation.

Fig. 3 is a fragmentary section taken substantially on the line 3—3 of Fig. 2.

Fig. 4 is a fragmentary front elevation.

Referring to the drawing, wherein is illustrated the preferred form of my invention, and in which like numerals of reference indicate corresponding parts throughout the several views, the window frame A is of the usual construction and near each side stile I have provided a guide rod 1 disposed vertically and fixed to the window casing as 55 shown in Figs. 1 and 2 of the drawing. The upper end of each guide rod is secured by at-

taching flanges 2 to the upper cross piece of the window frame while the lower end of each guide rod is fastened to a bracket 4 projecting laterally from the side of the frame 60 at a point above the sill.

A plurality of shade sections are mounted to be vertically adjustable on the guide rods 1 and each section includes the retaining strips 5 which have their upper ends bent to 65 provide ears 6 having openings for the reception of the guide rods 1 to permit the retaining strips to be vertically adjusted on the guide rods. Near the upper end of each strip 5 I have attached a flat spring 7 one 70 end of which is secured to the strip while the opposite end is provided with an arcuate notch for engaging the surface of the guide rod 1. This spring acts to hold the strip at an angle as shown to advantage in Fig. 3 of 75 the drawing. Each complete section includes the frame bars 8 which extend transversely across the frame and are fastened near their ends to the upper and lower ends of the retaining strip 5. In this manner a substantially 80 rectangular frame section is provided and the shade panels 9 are fastened to the frame bars 8 to complete the section. The panels 9 are preferably constructed from the material generally used to construct window 85 shades and it will be obvious that when the shades are arranged as shown in Figs. 1 and 2 the complete shade covering for the window will be provided.

As shown in the drawing, the uppermost 90 shade section is permanently secured to the top of the window frame by a top cross strip 10 to which the panel 11 is secured. The lower edge of this panel is unattached to permit the panel to swing outwardly whereby the lower shade section may be thrust upwardly to raise the shade. It will be understood, however, that this panel 11 may be constructed in the manner of the other panel 95 so that it may be raised and lowered in a 100 like manner.

For the purpose of holding all of the shade sections in operative closed position, I have provided each section with supporting strips 12 one of which is fastened to 105 each upper frame bar 8 near the end thereof. This strip projects outwardly and is adapted to receive the lower marginal edge of the upper section of the adjacent shade section to hold the different sections in raised position. To adjust any of the sections, it is 110 merely necessary to slightly raise the lower

edge of the section out of engagement with the corresponding strips and then slide the section to the desired position. And since any of the sections may be independently 5 adjusted it will be obvious that any portion of the window may be exposed to the light.

From the foregoing it will be obvious that a very simple and durable window shade has been provided, the details of which 10 embody the preferred form. I desire to be understood, however, that slight changes in the minor details of construction may be made without departing from the spirit of the invention or the scope of the claims here- 15 unto appended.

Claims—

1. A window shade comprising a plurality of vertically adjustable sections, each including a frame having panel fastened 20 thereto, portions of the frame being projected from the said frame at the ends thereof to form ears having openings engageable with the said rods to permit a sliding movement of the said frames on the rod, the front 25 of each frame at the upper edge thereof being provided with clips adapted to receive the bottom edge of the adjacent frame to support the latter when the frames are in operative position, and spring clips attached 30 to the frame and including flat spring members having arcuate portions embracing a portion of the rod to maintain the said frame in spaced relation from the said rod.

2. A window shade comprising a plurality 35 of shade sections, a pair of guide rods

mounted in vertical position, each frame section including a retaining strip having ears provided with openings for receiving the said guide rods, a pair of frame bars for each section attached to the said retaining strips, and a shade panel mounted on each pair of frame bars and guide strips. 40

3. A window shade comprising a plurality of shade sections, a pair of guide rods mounted in vertical position, each frame 45 section including a retaining strip having ears provided with openings for receiving the said guide rods, a pair of frame bars for each section attached to the said retaining strips, and a shade panel mounted on 50 each pair of frame bars and guide strips, each section having a pair of clips attached thereto, near its upper edge to receive the corresponding edge of the next adjacent section. 55

4. A window shade comprising a plurality of adjustable shade sections, guide rods disposed vertically and having the sections connected thereto for vertical adjustment, and resilient elements secured to the sections and 60 engageable with the vertical guide rods to maintain the sections in spaced relation from the guide rods.

In testimony whereof I affix my signature in presence of two witnesses.

CHARLES E. HOBSON.
